Attorney

UNITED STATES PATENT OFFICE.

JAMES W. FERER, OF RENOVO, PENNSYLVANIA, ASSIGNOR OF ONE-THIRD
TO ALBERT E. WEIL, OF SAME PLACE.

BALUSTER.

SPECIFICATION forming part of Letters Patent No. 310,807, dated January 13, 1885.

Application filed November 26, 1884. (No model.)

To all whom it may concern.

Be it known that I, JAMES W. FERER, a citizen of the United States of America, residing at Renovo, in the county of Clinton 5 and State of Pennsylvania, have invented certain new and useful Improvements in Balusters; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention relates to certain new and useful improvements in composite balusters or newel-posts; and my invention consists in a post or column which is made up of different parts, and provided with a central pillar 20 for retaining the ornamental parts upon each other, the top and base piece of the baluster being provided with screw-threads for attaching the same to the support and hand-rail or object to be supported, as will be hereinafter 25 more fully set forth.

My invention also consists in the construction and combination of the parts, as will be hereinafter fully set forth, and specifically pointed out in the claims.

30 In the accompanying drawings, which illustrate my invention, Figure 1 is a side view; Fig. 2, a view partly in section.

A represents a pillar or shaft, which from its bottom portion, a , to an intermediate portion, a' , is circular in cross-section, and above the point a' this pillar or shaft may be of any ornamental construction, the ornamental portion a'' being of greater diameter than the body portion, so as to form a shoulder upon 35 its under side, and the upper portion of the shaft A at its end is provided with a screw-thread, A' , which screw-threaded portion is of less diameter than the pillar, thus providing at its upper portion shoulders at the end of the screw-threaded portion A' . The lower 40 end of the pillar A is provided centrally with a downwardly-projecting pin, a''' , which enters a recess in the central portion of the base-piece. The pillar A, its upper ornamental

portion, and the screw-thread thereon are made 50 of a single piece or formed integral with each other. The base B is provided on its under side with a screw-thread, b , and its upper portion is hollowed out, the edge of said base-piece being provided internally with a flange, 55 b' .

Over the pillar A are placed ornamental sections C D. The lower section, D, is preferably made of metal with a smooth exterior, while the section C may be made of wood, the 60 exterior portion of which is ornamented. The two sections C D form the shaft of the baluster and are held in position by the pillar A. If desirable, a collar, E, may be placed over the lower end of the pillar A, which collar is 65 of sufficient thickness to fill the space between said collar and the interior of the base-piece B. The upper portion, A' , of the pillar A enters the under side of the hand-rail of the baluster, while the portion b enters the floor 70 or lift of the step, and said portion b is threaded in an opposite direction from the upper screw-threaded portion. If desirable, the hand-rail and floor may have metal sockets attached thereto, which are internally screw-threaded 75 for the reception of the right and left hand screws $A' b$. The base B, section D, and upper portion of the pillar are preferably nickel-plated or otherwise ornamented.

From the foregoing construction it will be 80 seen that I provide a baluster which is of highly ornamental construction, and is made up of parts that can be readily connected to each other and attached to the base-support and hand-rail, also that as the base-piece and 85 section above the same are made of metal they are not liable to be injured by objects striking against the same.

I claim—

1. In a baluster, the combination of the 90 pillar A, screw-threaded at its upper portion, sections C D, encircling said pillar, and a base-piece with a screw-threaded portion which projects on its under side, substantially as shown, and for the purpose set forth. 95

2. In a baluster or newel-post, a hollow base-piece, B, with a screw-threaded portion formed on its under side, the rim of said base-

piece forming a support for the hollow section D, in combination with a pillar, A, ornamented at its upper end and provided with a screw-threaded portion, substantially as shown, and

5 for the purpose set forth.

3. In a baluster, a metallic pillar, A, having a lower cylindrical portion and pin, a'', said pillar terminating at its upper portion in a screw-thread, in combination with the
10 hollow ornamental sections C D, encircling the

lower portion of the pillar, and a hollow base-piece, B, with screw-threaded portion b and collar E, the parts being organized substantially as shown.

In testimony whereof I affix my signature in 15 presence of two witnesses.

JAMES W. FERER.
